CLAIM

The ornamental design for a solar powered charger, as shown and described.

DESCRIPTION

FIG. 1 is a top plan view of a solar powered charger, showing my new design, in an open configuration;

FIG. 2 is a bottom plan view thereof, in an open configuration;

FIG. 3 is a bottom and side perspective view thereof, in an open configuration;

FIG. 4 is a bottom and side perspective view similar to FIG. 3, shown in an alternate configuration;

FIG. 5 is a side elevation view thereof;

FIG. 6 is another side elevation view thereof;

FIG. 7 is another side elevation view thereof;

FIG. 8 is another side elevation view thereof;

FIG. 9 is a bottom plan view thereof, in a closed configuration;

FIG. 10 is a top plan view thereof, in a closed configuration;

FIG. 11 is a bottom and side perspective view thereof, in a closed configuration;

FIG. 12 is a top and side perspective view thereof, in a closed configuration;

FIG. 13 is a front elevation view thereof;

FIG. 14 is a rear elevation view thereof;

FIG. 15 is a side elevation view thereof; and,

FIG. 16 is another side elevation view thereof.

The name SOLIO®, forming part of the claimed design, is a registered trademark owned by Better Energy Systems, LTD.
